(57) **CLAIM**

The ornamental design for a tape cassette for label printer as shown and described.

DESCRIPTION

FIG. 1 is a perspective view of the tape cassette for label printer;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dot-dash chain lines, and evenly spaced broken lines immediately adjacent to the shaded areas, depict the bounds of the claimed subject matter and form no part of the claimed design. All other evenly spaced broken lines depict parts of the tape cassette for label printer that form no part of the claimed design.

1 Claim, 7 Drawing Sheets
